TAMPER CONTROL MECHANISM

Filed Nov. 10, 1927

UNITED STATES PATENT OFFICE

HENRY C. PARKER, OF MAYWOOD, NEW JERSEY, ASSIGNOR TO BERGEN BUILDING BLOCK COMPANY, A CORPORATION OF NEW JERSEY

TAMPER CONTROL MECHANISM

Application filed November 10, 1927. Serial No. 232,267.

The present invention relates to improvements in tamping machines, such, for example, as are used in concrete block manufacture. In one type of concrete block machine employing the tamping principle, a mold box is filled with loose concrete and then the tamping mechanism is started, causing a series of tampers or hammers to drop successively on the loose concrete, packing it tightly into the mold. After these tampers have made a certain number of strokes, depending on the type of the block being made and the nature of the concrete, they are arrested by operation of a lever and the tamping ceases. The strength of the concrete block depends to a large extent on the number of times the concrete is struck by the hammers. It is customary to pay the operatives on a piece-work basis and, hence, they are interested in making the blocks as fast as possible, with the result that they are apt to reduce the number of tamping strokes below that necessary or desirable, and it is a source of constant annoyance to the foreman or supervisor to watch the operators and make sure that the correct number of tamping strokes are given to each block.

It is an object of the present invention to overcome this difficulty by providing means which will automatically prevent arresting of the tamping operations until the requisite number of strokes have been made by the hammers.

Another object of the invention is to provide means for expediting the operation of the tamping mechanism. Heretofore it has been necessary not only to turn on the tamping mechanism by hand but also to turn it off manually. With my improved control mechanism, the tamping mechanism may be automatically turned off after the requisite number of tamping strokes have been delivered.

Another object of the invention is to provide a mechanism for controlling the number of tamping strokes, which mechanism is in the form of an attachment that can be applied to existing machines.

With these and other objects in view, which

5 movement of the invention will now be described and thereafter the novelty and scope of the invention will be defined in the claims.

In the accompanying drawing,

Fig. 1 is a side elevation of a portion of a 55 tamping machine equipped with the improved control mechanism, certain parts being broken away to illustrate details of construction;

Fig. 2 is a rear elevation of the same; and 60

Fig. 3 is a fragmentary side elevation of the tamping and control mechanism with brackets and supports therefor removed and showing the parts in operative position.

The main frame of the tamping machine 65 is rectangular in form, comprising a pair of vertical frame members 10 and top and bottom horizontal members 11 and 12, respectively. Mounted to slide through the members 11 and 12 are vertical tamping rods 13 70 which carry hammers 14 at their lower ends. Each tamping rod carries a lifting finger 15 which projects forward and is provided at the rear with a forked extension 16 adapted to embrace a vertical guide rod 17. The 75 guide rods 17 are supported at their upper ends in the frame member 11 and at their lower ends by a cross bar 18. A transverse shaft 19 is supported in suitable bearings 20 carried by the vertical frame members 10 and 80 fixed to this shaft are a number of arms 21, each provided at its free end with a roller 22. There is an arm for each lifter finger 15 and the position of the arms is such as to 85 strike the lifter fingers and lift the rods to the position indicated in Fig. 1. The arms 21 are angularly disposed relatively to one another so that the rods 13 will be successively lifted.

Each rod carries at its upper end a safety 90 collar 23 adapted to engage a spring 23' at the top frame member 11 and prevent the rod from dropping out of the frame should there be no mold under the hammers. Normally the rods are maintained in the position 95 shown in the drawing by means of levers 24 which engage collars 25 secured to the rods. Each lever 24 is of bell-crank form having a laterally projecting arm 26. The levers are mounted in a rocker bar 27 which extends 100

across the frame and is formed with trunnions 28 at each end journaled in the side members 10. One of the trunnions extends through the frame and has a handle 29 fixed thereto, by which the bar 27 may be rocked. The rocker bar 27 is preferably in the form of a right angle in cross-section with one flange of the bar serving to support the arm 24, and the other flange providing an abutment for a spring 30 which fits between said other flange and the arm 26. The spring thus normally urges the arm 24 toward the rods 13.

The mechanism so far described is a standard construction and forms no part of the present invention. In operation the handle 29 is raised, swinging the arms 24 clear of the stop collars 25 and permitting the rods 23 to drop. Thereupon the arms 21 successively raise the rods, by engaging the fingers 15, and permit the rods to drop as the rollers 22 roll off the ends of the fingers. This operation continues until the operator lowers the handle 29, pressing the lever arms 24 against the rods. Thereafter as each rod is raised by its arm 21, the rod is thrown far enough by its momentum for finger 15 to clear the roller 22 and, in this position, the corresponding lever arm 24 snaps under a stop collar 25 arresting the rod in its raised position.

My control mechanism is carried in the main by a bracket 31 which is attached to one of the side members 10 and to the cross bar 18. This bracket is formed with a pair of flanges which provide bearings for a shaft 32. Attached to the rocker bar 27 by any suitable means is a bracket 33 which provides a pivotal support for the lower end of an arm 34, the upper end of which is forked to embrace the hub of a disk 37 mounted on the shaft 32. The hub is preferably formed with an annular groove to receive the forked end of the arm. Mounted on this arm 34 is a pin roller 35 which normally engages a notch 36 in the disk 37. The latter is pinned to the shaft 32. Attached to the bracket 31 are two bracket extensions 38 and 39, respectively, which provide bearings for a shaft 40. Fixed upon the shaft 40 is a pulley 41 and a pinion 42. The latter meshes with a gear 43 secured to the shaft 32. A loose endless belt 44 runs about the pulley 41 and shaft 19. Normally the shaft turns idly in the belt without turning the pulley, but, when it is desired to actuate the pulley, a belt tightener is operated. This belt tightener consists of an idler 45 mounted on the end of an arm 46, the opposite end of which is pivotally supported by the bracket extension 39. A connecting rod 47 serves to connect the arm 46 with the arm 34.

In operation, when the handle 29 is lifted to release the tamping rods, the arm 34 is lowered so that the roller 35 clears the notch

36 in the disk 37. At the same time the idler 45 is drawn down, by means of the connecting rod 47, to take up the slack in the belt 44, thereby causing the pulley 41 to be driven by the shaft 19. By this means, the shaft 70 38 is rotated and, through the pinion and gear connection, the shaft 32 is also rotated. As rotation occurs, the disk 37 revolves so that the notch 36 no longer registers with the roller 35. This prevents the arm 34 from 75 rising and the levers 24 from moving into position to engage the collars 25, until the disk has made one complete rotation. The tamping will, therefore, continue until the notch 36 has been brought around to position 80 for the roller 37 to enter therein again, which it will do automatically under impulse of the spring 29'. In the meantime the operator of the machine cannot stop the tamping operation once it has started until the notch 36 has 85 been revolved into registry with the pin 35. The number of tamping strokes will depend upon the gear ratio between the shaft 19 and the disk 37. This gear ratio may be varied by changing the relative sizes of the pinion 90 42 and gear 43 so as to insure a predetermined number of tamping strokes for each operation of the machine. The disk 37 may also be provided with a number of notches 95 36 so angularly spaced as to limit the tamping period to a fraction of the period of rotation of the disk.

While I have described my tamping control mechanism as applied to a specific machine, it will be obvious that the same principle could be employed with other types of tamping machines and also that the same system of control could be used in connection with the machines that are not necessarily employed in concrete block manufacture. 100 I, therefore, do not limit myself to the specific adaptation described nor to the specific construction shown, but consider myself at liberty to make such variations, alterations, modifications and arrangements of structure 105 and parts as fall within the spirit and scope of the appended claims.

Having thus described my invention, what I claim and desire to secure by Letters Patent is:

1. The combination with a tamping machine comprising a tamping member, a power shaft, means carried by the shaft for intermittently lifting and releasing the tamping member, an arrestor for holding the tamping member clear of said means and a handle for disengaging the arrestor from the tamping member, of a spring tending to restore the arrestor to holding position, a disk non-positively rotated by said shaft and formed with a peripheral notch, and an arm connected to the handle and normally engaging the notch, whereby, on operation of the handle, the arm will be withdrawn from the notch to release the disk, and the arrestor 125 130 135

will be held in disengaged position until the disk has rotated sufficiently to bring the notch again into position to receive the arm.

2. The combination with a tamping machine comprising a tamping member, a power shaft, means carried by the shaft for intermittently lifting and releasing the tamping means, an arrestor for holding the tamping member clear of said means, and a handle for disengaging the arrestor from the tamping member, of a spring tending to restore the arrestor to holding position, a rotatable disk, driving gear including a friction clutch connecting shaft and the disk for driving the latter, the disk being formed with a peripheral notch, an arm connected to the handle and having a pin normally engaging the notch, whereby on operation of the handle the pin will be withdrawn from the notch, and means connected with the arm for operating the friction clutch when the arm is withdrawn from the notch, the arrangement being such that the arm will be held in withdrawn position by the disk and the arrestor will be held disengaged by the arm until the disk has made one complete rotation returning the notch to position to receive the pin.

3. The combination with a tamping machine comprising a tamping member, a power shaft, means carried by the shaft for intermittently lifting and releasing the tamping member, an arrestor for holding the tamping member clear of said means, and a handle for releasing the arrestor from the tamping member, of a spring tending to restore the arrestor to holding position, a rotatable disk, driving means including a normally loose belt connecting the disk and the shaft for driving the disk, means for tightening said belt, the disk being formed with a peripheral notch, an arm connected to the handle and having a pin normally engaging the notch and a link connecting the belt tightening means to the arm, the parts being so arranged that, when the handle is operated to release the arrestor, the arm will operate to withdraw the pin from the notch and the belt tightener will be operated to cause rotation of the disk thereby preventing return of the handle and the arrestor to normal position until the notch has been brought to position to receive the pin.

4. The combination with a tamping machine having a tamper, means for operating the same, an arrestor for holding the tamper in inoperative position and means controllable at will for withdrawing the arrestor to permit the tamper to operate, of means for preventing return of said arrestor to holding position except at predetermined periods after the withdrawal of the arrestor.

5. The combination with a tamping machine having a tamping member, means for operating same, an arrestor for holding the tamper in inoperative position and means

operable at will for withdrawing the arrestor to permit the tamper to operate, of means for holding the arrestor in withdrawn position for a predetermined interval measured from the time of the withdrawal of the arrestor.

6. The combination with a tamping machine having a tamping member, means for operating said member, an arrestor for holding said member in inoperative position and manually controlled means for withdrawing the arrestor, of means tending normally to return the arrestor, retaining means for preventing return of the arrestor to holding position until it has remained in the withdrawn position for a predetermined interval and means for releasing the retaining means as soon as said interval has elapsed.

7. The combination with a tamping machine comprising a tamping member, lifting means for intermittently lifting and releasing the tamping member, a detent for holding the tamping member clear of said means and a handle operable at will to disengage the detent from the tamping member, of a latch for holding the detent in disengaged position, and means operating to release the latch at a predetermined time after the detent has been disengaged.

8. The combination with a tamping machine comprising a tamping member, a lifting means for intermittently lifting and releasing the tamping member, a detent for holding the tamping member clear of said means and a handle operable at will to disengage the detent from the tamping member, of a latch for holding the detent in disengaged position, means operating to release the latch at a predetermined time after the detent has been disengaged, and a spring for returning the detent to holding position.

9. An attachment for a tamping machine having a manually operable device for controlling the starting and stopping of a tamper, said attachment comprising means to prevent operation of said device to stop the tamper except at predetermined intervals after said device has been manually operated to start the tamper.

In testimony whereof, I have signed this specification.
